FUNDAMENTAL FREQUENCY SELECTOR FROM SPEECH SOUND WAVES (FOR ALL VOICES)

Meguer V. Kalfaian, Los Angeles, Calif.

Application March 24, 1958, Serial No. 723,498

6 Claims. (Cl. 179—1)

This invention relates to the analysis of speech sound waves, and more particularly, to systems and means for instantaneous determination of the fundamental (pitch) frequencies of speech sound waves.

A fundamental frequency of speech sound waves is usually referred to the repetition rate of replica wave patterns, each one of which is formed by certain combinations of resonances having definite amplitude levels and frequency ratios one with respect to another. In ordinary speech, however, the frequency positions of these resonances in any combination for a particular sound, shift widely for each phonetic sound, and thus the repetition rate of these wave patterns also changes widely. In various modes of speech sound wave analysis, each wave pattern is analyzed separately for phoneme recognition, or for other purposes, for example, in the practice of spoken sound bandwidth compression by way of transmitting one or two of the successively repeating wave patterns and reconstructing the remaining wave patterns at a receiving terminal end, and accordingly, instantaneous determination of these varying fundamental frequencies (marking points at the beginning and ending of each wave pattern) is extremely desirable.

The succession of the wave patterns is effected by regular puffs of air from the glottis, which are set into vibration in the momentarily formed resonant cavities of the vocal system. As each puff of air enters the resonant cavities of the vocal tract, there forms a high-peaked surge, which produces the first constituent wave of a wave pattern higher in amplitude (major peak) than any of the other waves (minor peaks) contained therein. Thus by selecting the major peaks as marker points of the arrival and ending of wave patterns, one cycle portions of the varying fundamental frequencies of spoken sound waves may be readily determined. I had first described this mode of fundamental frequency selection in my U. S. Patent No. 2,613,273, October 7, 1952, filed January 23, 1947, and in my following patents No. 2,673,893, March 30, 1954; No. 2,708,688, May 17, 1955. Also my latest improvement of fundamental frequency selection in my patent application Serial No. 684,205, September 16, 1957, over which further improvements are made by the presently disclosed fundamental frequency selector.

Major peak selection may be utilized for analytic purposes of various phases of the spoken sound waves. For example, it is desired that the number of words spoken within a given time period be counted. To accomplish this, we may first refer to the condition that a spoken phonetic sound consists of a repetition of wave patterns. The repetition frequency rate of these wave patterns is determined by repeated puffs of air from the glottis, which is variable, and ranges a frequency rate from 60 to 600 repetitions per second. In pronouncing a series of words, however, the minimum time that the physical elements can go through in making a complete cycle of change in position is not less than $\frac{1}{60}$ second. Consequently, the puffs of air must stop functioning, for at least $\frac{1}{60}$ of a

2

second before a succeeding word is pronounced. Since the fundamental frequency selector, as disclosed herein, will produce marker signals at the arrival of successive wave patterns, it is possible to measure the time periods 5 of these major peak signals, and derive output signal whenever the time period between any two major peak signals exceeds a predetermined time period. These derived output signals may then be represented as the number of words spoken. Accordingly, it is contemplated herein to provide means, in conjunction with the major peak selector, a word counter, in accordance with the invention.

The mode of operation of the circuitry disclosed herein will be better understood from the following detailed 15 specification and by reference to the accompanying drawings, wherein, Fig. 1 is a schematic arrangement of the major peak selector; Fig. 2 is an oscillographic waveform of the phonetic sound "N," in combination with marker square waves, as obtained from the arrangement 20 of Fig. 1, coincident with the major peaks of said waves; Fig. 3 is a simplified arrangement of Fig. 1 for describing its operation; Figs. 4 and 5 are waveforms involved in describing the function of Fig. 3; Fig. 6 is an arrangement for deriving word counting signals from the 25 output major peak signals of the arrangement given in Fig. 1, in accordance with the invention; and Fig. 7 is a modified arrangement of Fig. 1.

In ordinary speech, the succession of wave patterns are not always distinguished by highly emphasized major 30 peaks, and they are sometimes lost with the minor peaks. For simplicity of illustration, a partly irregular waveform of the sound "N" is shown in Fig. 1. In this drawing (read the time base from right to left hand of the sheet), the major peaks are designated as P1, P2, P5, P8, 35 and marked by pulses of the square waves drawn immediately below the sound waves. The major peaks between P1 and P5 are quite distinguishable, but between P5 and P8, they start declining, and the minor peaks could be mistaken for major peaks when passed through a 40 series connected rectifier and an RC network of short recovery time constant. Accordingly, the principal object of the present invention is to provide a circuit arrangement which is functionally capable of standardizing these amplitude changes as fast as they may occur.

The basic principles of operation of the fundamental frequency selector, as shown in Fig. 1, may be best described by the simplified circuit given in Fig. 3. In this arrangement, assume first that the electron tube V1 is 45 of a commercially available type 5915, which contains two separate electron intensity control grids G1 and G2, so that its transconductance as well as the plate conductance may be controlled by any one of these two control grid elements. One of the control grids, for example, G2 is zero biased with respect to the cathode element, and the other grid, for example, G1, is biased at three volts negative with respect to the cathode element. The normal three volt bias renders this particular tube 50 operative at a non-linear curve of the grid-versus-plate swing with minimum transconductance. In this state of the arrangement, assume that a sine wave of three volts peak is applied to the grid G1, the voltage of which is amplified in the plate circuit resistance R1. This amplified voltage is rectified through rectifier diode D1, through coupling capacitor C1, and applied upon the control grid G2 in degenerative direction. During the 55 positive excursion of the input sine wave at G1, the transconductance of the tube increases, while at the same time the rectified voltage applied upon grid G2 decreases the transconductance. Here it will be noted that the greatest degenerative feedback would occur at the peak of the input sine wave at G1; but since at this point the bias at G2 had been driven highly negative, the voltage at G2

and R_2 drops to maximum negative until the tube becomes almost non-conductive. In this degenerative feedback process, the feedback negative voltage charges in parallel connected capacitor C_2 ; suddenly, and decays gradually, keeping the tube transconductance low, so that further positive swing (minor peaks) upon grid G_1 does not cause appreciable feedback voltage from across R_1 , until the negative voltage at G_2 has resumed close to cathode potential. The net result is that, first, during the initial degenerative feedback a maximum negative potential is developed across C_2 with greatly reduced excitation immediately thereafter, and second, the magnitude of initial charge across C_2 becomes almost identical with different amplitudes of applied sine wave voltage upon grid G_1 , since as stated, the amplified potential across R_1 causes maximum swing of the tube transconductance even with small voltage swing upon the input grid G_1 .

To illustrate graphically the waveform difference upon grid terminals G_1 and G_2 , Figs. 4 and 5 show different operating conditions. The graph at Fig. 4 shows a sine wave of three volts peak applied upon the control grid G_1 , and the resultant wave at G_2 . The graph in Fig. 5 shows how the amplitude of the voltage waveform obtained at the control grid G_2 is increased with respect to the sine wave voltage of small amplitude applied upon the control grid G_1 . Both the amplitudes and waveform of the applied and derived potentials in Figs. 4 and 5 are drawn approximately proportionally, so as to show the peak exaggeration and instantaneous gain control action of the arrangement in Fig. 3. The duties imposed upon grids G_1 and G_2 may be reversed with equivalent operational results.

The graphical illustrations in Figs. 4 and 5 indicate that complete amplitude control is not obtained from a single stage of the arrangement given in Fig. 3. Since enormous variation occurs in the amplitude of normal speech sound waves, it is desirable that more than a single stage of the arrangement of Fig. 3 is used for selection of the major peaks.

Fig. 1 is the complete schematic arrangement for selecting major peaks of the spoken sound waves. In this arrangement, there are used three stages of automatic gain control circuits comprising tubes V_2 — V_4 ; three stages of major peak selector circuits comprising tubes V_5 — V_7 ; and a flip-flop trigger circuit comprising cross-coupled trigger tubes V_8 — V_{13} . The function of automatic gain control circuits is substantially the same as of the major peak selector circuits, but with different control adjustments, and the function may be described as in the following:

Referring to Fig. 1, the spoken speech sound wave is received by a microphone 1, the voltage variations of which are amplified in the plate circuit resistor R_3 through cathode excitation of double triode vacuum tube V_{14} . The signal voltage developed across R_3 is applied through coupling capacitor C_3 , to the first control grid G_3 of the first gain-control tube V_2 . The positive going signal in this tube is amplified across the plate circuit resistor R_4 , and fed back to the second control grid G_4 in negative direction, through coupling capacitor C_4 ; diode D_2 ; and parallel connected RC circuit comprising resistor R_5 and capacitor C_5 . The RC time constant of R_5 and C_5 is pre-adjusted much longer than the time constant adjusted for major peak selection, so as to average out the wide variation of amplitude changes in longer time than necessary for major peak selection. The amount of feed back, however, is made small, so that the required amount of gain control is obtained by several stages, for better peak regulation. This is done by choosing a small value for the resistor R_4 . For peak amplitude control, the negative feedback voltage from R_4 is normally biased at a positive potential across battery B_1 , through load resistor R_6 ; so that gain-control voltage is not fed back to the control grid G_4 of V_2 until the

negative feedback voltage is higher than the positive bias potential of B_1 . Thus the storage capacitor C_5 charges negatively when the feedback voltage from across resistor R_4 exceeds the bias potential of B_1 , and discharges through parallel connected resistor R_5 gradually until another feedback voltage arrives for recharging.

Due to the pre-fixed polarity of diode D_2 , it is noted that only positive going input signal is utilized for gain control operation. Thus, the output signal of each gain control circuit must be first phase inverted before applying to a succeeding gain control circuit. This is done by applying the voltage signal from across R_4 to one of the control grids (G_5) of double triode tube V_{15} , through coupling capacitor C_6 and load resistor R_7 . This applied signal potential is phase inverted across plate circuit resistor R_8 , and coupled to the first control grid of V_3 through coupling capacitor C_{11} . The circuitry and function of gain-control tube V_3 is similar to the circuitry and function of gain-control tube V_2 , and accordingly, further description is not necessary herein. The feedback component parts, however, are: coupling capacitor C_8 ; rectifier diode D_3 ; parallel connected RC circuit comprising resistor R_9 and capacitor C_9 ; and load resistor R_{10} , which connects to the peak-limiting positive bias source B_1 . In a similar mode, as described by way of the first gain-control section, the feedback voltage developed across plate circuit resistor R_{11} of V_3 is applied to the control grid G_6 of double triode tube V_{15} , through coupling capacitor C_{10} , for phase inversion across the plate circuit resistor R_{12} of V_{15} . This phase inverted signal potential across resistor R_{12} is applied to the first control grid of a third stage of gain-control tube V_4 , through coupling capacitor C_{11} . The circuitry and function of this third stage is also similar to the circuitry and function of gain-control tubes V_2 and V_3 , and accordingly, further description is not necessary to be given herein. The feedback component parts, however, are: feedback coupling capacitor C_{12} ; rectifier diode D_4 ; parallel connected RC circuit comprising resistor R_{13} and capacitor C_{13} ; and load resistor R_{14} , which connects to the peak limiting positive potential of battery B_1 .

For the function of major peak selection, the negative feedback voltage developed in the plate circuit resistor R_{15} is first phase inverted in the double triode tube V_{14} . This is done by coupling the signal voltage across R_{15} to the control grid G_7 of tube V_{14} , through coupling capacitor C_{14} . The phase inverted signal voltage across plate circuit resistor R_{16} of this tube is applied to the first control grid G_8 of the first major peak selector tube V_5 , through coupling capacitor C_{15} . This applied signal potential is amplified in the plate circuit resistor R_{17} , and fed back in degenerative direction to the second control grid G_9 of V_5 . The feedback loop is accomplished through coupling capacitor C_{16} ; rectifier diode D_5 ; and parallel connected RC circuit comprising resistor R_{18} and capacitor C_{17} . Unlike in the gain-control circuitry of the first three stages, comprising tubes V_2 — V_4 , the feedback signal voltage is zero biased through load resistor R_{19} ; instead of the positive bias from battery B_1 . Also, the input signal-potential upon the first control grid G_8 is amplified in large magnitude in the plate circuit resistor R_{17} before being fed back to the second control grid G_9 . The circuitry and function of this stage has already been described by way of the example given in Fig. 3, and also by the graphical illustrations in Figs. 4 and 5. Accordingly, further descriptive matter is not necessary herein. As a brief reminder, however, the selected major peak is obtained at the second control grid G_9 of this tube, by way of fast charging and slow discharging action of storage capacitor C_{17} . As stated in the foregoing, only the positive going signal impressed upon the first control grid, for example, grid G_8 of V_5 , is effective for feedback and major peak selection. Accordingly, for each additional stage of feedback major

peak selection the output signal (stored signal-potential at the second control grid G9 of V5) must be phase inverted before being applied to the succeeding stage. Thus, the output of V5 (the second control grid G9 of V5) is directly connected to the control grid G10 of phase inverter tube V16, and the phase inverted signal potential across plate circuit resistor R20 is applied to the first control grid G11 of the second stage of major peak selector tube V6, through coupling capacitor C18. The circuitry and function of this stage (V6) is similar to the circuitry and function of the first stage of major peak selector tube V5, and accordingly, further description is not necessary to be given herein. The feedback loop component parts, however, are: plate circuit resistor R21; feedback coupling capacitor C19; rectifier diode D6; and parallel connected RC circuit comprising resistor R22 and capacitor C20. In this second stage of major peak selection, the feedback signal voltage is normally biased 3 volts positive through load resistor R23, as shown. This small bias is found useful in practice, for cancelling out some spurious noise voltages. However, the advantage is not great enough to render this positive bias arrangement absolutely necessary, and this positive bias may be dispensed with, if so desired.

For the third stage of major peak selection, the output negative major peak voltage developed across C20 is applied directly to the control grid G12 of phase inverter tube V16, and the phase inverted major peak voltage across plate circuit resistor R24 is applied to the first control grid G13 of the third stage major peak selector tube V7 through coupling capacitor C21. The circuitry and function of the third stage of major peak selector tube V7 is similar to the first and second stages of major peak selector tubes V5, V6, and also to the exemplary arrangement described by way of the circuit given in Fig. 3. Accordingly, further descriptive matter is not necessary herein. The feedback component parts, however, are: plate circuit resistor R25; feedback coupling capacitor C22; rectifier diode D7; and parallel connected RC circuit comprising resistor R26 and capacitor C23.

The final negative major peak voltage obtained across C23 is applied directly to the control grid G14 of the amplifier section of double triode V17, and the amplified major peak voltage across plate circuit resistor R27 is applied to the control grid G15 of the phase splitting section of double triode V17. The amplified major peak voltage impressed upon the control grid G15 of V17 is produced in positive polarity across cathode circuit resistor R29 and in negative polarity across plate circuit resistor R28 of tube V17. These positive and negative major peak signals from across R28 and R29 are applied to the parallel connected second control grids of V12, V13 through coupling capacitor C26, and to the parallel connected second control grids of V10, V11 through coupling resistor R28 of tube V17. These positive and negative signals used as the exciter tubes of cross-coupled flip-flop circuit comprising trigger tubes V8 and V9, the function of which may be described as in the following:

Assume initially that the plate supply potential is applied upon the tube V8. The unloaded storage capacitors C27 and C28 will charge, through conductance of grids G16 and G17, to the plate supply potential. But due to plate to grid cross coupling between the two sections of V8, one section will conduct and apply a large negative bias upon the control grid of the other section; thus effecting a stable conducting and non-conducting condition of the double triode V8. The same relates to the double triode tube V9, by way of the cross-coupled storage capacitors C29 and C30.

The trigger tubes V8 and V9 are cross coupled one with respect to the other by way of the mixer tubes V10, V11, in the following manner: The control grid G18 of V9 is directly connected to the first control grid of V11, and the control grid G19 of V9 is directly connected to the first control grid of mixer tube V10. Similarly, the

control grid G16, of V8 is directly connected to the first control grid of mixer tube V12, and the control grid G17 of V8 is directly connected to the first control grid of mixer tube V13. In this state, the second control grids of mixer tubes V12 and V13 are normally biased to plate current cut off, and the second control grids of mixer tubes V10 and V11 are zero biased. Thus, assuming that the left handed section of trigger tube V9 is conducting, driving G18 at zero bias, and driving G19 at negative cut-off bias, the mixer tube V11 becomes conductive and draws plate current through plate circuit resistor R30. The current draw across resistor R30 applies cut-off negative bias upon the control grid G16 of V8, and the right handed section of the double triode V8 becomes conductive, rendering the left handed section non-conductive. When the negative major peak voltage arrives upon the second control grids of mixer tubes V10 and V11, these tubes are rendered inoperative without affecting the state of operation of the trigger tube V8. While simultaneously, when the positive major peak voltage arrives upon the second control grids of mixer tubes V12 and V13, these tubes become conductive, but since the first control grid of V12 is at negative cut-off bias by direct connection with the grid G16 of V8, the mixer tube V13 becomes conductive and draws plate current through resistor R31. The current passing through R31 applies negative cut-off bias upon the control grid G18 of the left handed section of double triode V9, rendering the right handed section conductive and the left handed section of V9 non-conductive. When the positive and negative major peak input signals cease to zero, the mixer tubes V12 and V13 again become idle and the mixer tubes V10, V11 operating. At this point, however, the first control grid of V11 has received negative cut-off bias by direct connection with the grid G18 of tube V9. Accordingly, V11 becomes non-conductive and V10 conductive; the latter tube drawing plate current through resistor R32. When current passes through R32, a large negative bias is applied upon the control grid G17 of trigger tube V8, rendering the right handed section of trigger tube V8 non-conductive and the left handed section conductive. Thus, each time the major peak input signals arrive at the flip-flop circuit just described, the trigger tube V9 changes its state of conductance, and at the end of the input signals the trigger tube V8 changes its state of conductance. This flip-flop action will produce square wave voltages, such as shown in Fig. 2, and may be obtained from any one of the plate circuits, for example, as designated by the letters (A) and (B) at the plate circuits of trigger tube V9.

Due to the open circuit grids of the flip-flop trigger tubes V8 and V9, the cross-coupling capacitors may initially be charged at a higher potential than the plate supply potential, when said supply is switched on, and render the trigger tube V9 inoperative, until said capacitors are discharged. To avoid time delay of this discharge, a resistor of high value, for example, 8 megohms, may be connected between G18 or G19 of V9 (or both grids) to ground.

It might be well to state that the arrangement as given in Fig. 1 is sensitive to 60 cycle noise, and the plate supply voltage must be well filtered. For convenience, each stage is shown with separate filtering, for example, by the resistors R33—R46 and bypass capacitors C30—C43. The gaseous regulator tubes V18 and V19 have been used in practice with more stable operation of the circuit, but they are not absolutely necessary and may be dispensed with, if so desired. It will be also of note to mention that, the number of stages for controlling the amplitude of the sound waves, and the number of stages used for selecting the major peaks may be different than shown in the arrangement of Fig. 1, as any number of stages may be utilized according to the requirements of a particular use. Also, the flip-flop circuit utilizing tubes V8—V13 may be of conventional design, if so desired.

Furthermore, the arrangement in Fig. 1 may utilize transistors, instead of vacuum tubes, without sacrificing functional operation. For example, the tetrode transistor will be suitable in replacing the gain-control and major-peak-selecting vacuum tubes.

In reference to the amplitude equalizing section of Fig. 1, it will be noted that each of the three stages (represented by tubes V2, V3 and V4) controls the amplitude of the input signal independently. In operation (reference to a single stage), the input signal rises in positive direction, which is amplified in the plate circuit impedance in negative direction. As this negative signal exceeds in amplitude of the peak limiting potential B1, the tube conductance lowers suddenly and causes positive signal in said plate circuit impedance. While this positive signal in the plate circuit may in some cases have high peak values for major peak selection, it is preferable that the wave-polarity in which the major peaks are to be selected is applied to each of the inputs of the amplitude equalizing tubes in negative polarity, so that the original waveform of the major peaks are preserved. Also, in view of the fact that wave distortion is multiplied by each of the added stages, the end result may impair the emphasis of the original major peaks. For this reason, a single stage of amplitude equalizer may be used separately to control as many series connected stages as desired. A practical arrangement, which has performed satisfactorily in actual tests, is shown in Fig. 7.

For simplicity of the present specification, and numeral references, all numerals directed to electronic tubes V5—V13, V16—V18, and the associated component parts with these tubes, are numbered the same as shown by the like parts in Fig. 1, as both the circuitry and operation of this section are the same, as explained in the foregoing; the only difference being that the negative bias -20 volts is changed to -9 volts, and the positive bias +3 volts is eliminated. The amplitude equalizing section comprises tubes V22 to V26, and their associated component parts are, for example, capacitors C43 to C61, and resistors R51 to R73. The operation of the amplitude equalizing section, just referred to, is as follows:

The input speech sound waves are applied to the first control grid of the first amplitude equalizing dual control grid tube V22, so polarized that, the major peaks to be selected appear in negative direction upon this grid. The amplified sound wave appears across the plate circuit resistor R51 (of V22) in negative polarity, and is further applied through coupling capacitor C49 to the control grid of phase inverting tube V23 (from across load resistor R53), for reestablishing the original major peaks in negative polarity in the plate circuit resistor R52 of tube V23. This last mentioned signal is applied through coupling capacitor C50 to the first control grid of the second amplitude equalizing dual control grid tube V24, from across load resistor R54. The second control grids of both amplitude equalizing tubes are connected in parallel, so that any control voltage applied upon these parallel connected grids can vary the amplitude of the amplified major peaks across the plate circuit resistor R63, of V24, the peak voltage of which appears in positive polarity across R63, and is applied upon the first control grid of the first major peak selector dual control grid tube V5, through coupling capacitor C52. The input speech sound waves are simultaneously applied upon the control grid G29 of V25, from across common load resistor R57, the amplified wave of which appears across the plate circuit resistor R55 of tube V25. This amplified voltage wave is coupled through coupling capacitor C53 to the control grid G21 of V25, from across load resistor R58, for further phase inversion across the plate circuit resistor R56 of this tube. The voltage wave across R56 is now in a direction in which the major peaks to be selected appear in negative polarity, and this wave is applied upon the first control grid of the auxiliary amplitude-control dual-control-grid tube V26, through coupling capacitor

C54, and from across load resistor R59. The amplified voltage wave across plate circuit resistor R60, of auxiliary control tube V26, is fed back to the second control grid in degenerative direction through unidirectional path comprising coupling capacitor C56; load resistor R62; rectifier diode D9; and parallel connected RC circuit comprising capacitor C51 and resistor R61. The rectifier D9 is so polarized that, during the negative excursion of the major peak upon the first control grid of V26, the amplified positive voltage across plate circuit resistor R60 is prevented from reaching the second control grid of this tube. Whereas, during the positive excursion of the sound wave upon the first control grid of this tube, an amplified negative voltage is applied upon the second control grid of V26, and reduces its transconductance. The negative voltage applied to the second control grid of this tube is stored across capacitor C51, with slow discharge by resistor R61. Due to square-law operation of the dual control grid tube V26, the amplified wave having higher amplitude across plate circuit resistor R60 of V26 is compressed by greater magnitude than the amplified wave having lesser amplitude; thus substantially equalizing the widely varying amplitudes of the input sound wave.

The second control grid of dual control grid tube V26 is directly connected to the second control grids of dual control grid tubes V22 and V24, so that the final amplified sound wave across plate circuit resistor R63 of V24 is simultaneously equalized in amplitude. In the latter case however, the sharp feed back control voltages from auxiliary control tube V26 are applied upon the second control grids of V22 and V24, during the opposite time periods of the actual major peak waves to be selected; thus avoiding any distortion of the selected major peaks. In a second alternative, which has proven practical in operation, the feedback to the selected major peaks is applied in regenerative direction. This is done by cancelling out the right hand triode section of double triode tube V25. In this manner, the sharp negative feedback from the anode circuit of the tube V26 is during the period in which the major peak upon the first control grids of V22 and V24 is in the negative direction, so that the positive major peaks at the anode circuits of V22 and V24 are exaggerated during said feedback periods. The circuitry change may be easily accomplished by disconnecting the wires at points (a), (b), and connecting a wire at point (c), as indicated in circles in the drawing. While three stages of amplitude equalization will give excellent results, the two stages as shown, comprising tubes V22 and V24, have proven very satisfactory in practical operation. According to the particular use, however, the tubes V22, V23, V24 may be eliminated, and the first control grid of major peak selector tube V5 may be excited by the positive peak waves appearing across the plate circuit resistor R60 of tube V26. The positive bias, +1.5 volts is used for the elimination of extraneous noise, but it may vary in amplitude, or be eliminated, if so desired. The remaining portion of the arrangement of Fig. 7 is similar to the like portion of the arrangement given in Fig. 1, and the function is similar as explained in the foregoing, so that further specification is not necessary herein.

In reference to the foregoing statement of deriving output word-counting signals from the selected major peak signals, as obtained from the arrangement of Fig. 1, the circuit arrangement in Fig. 6 is contemplated herein to provide the required functional operation. In this latter arrangement, the mixer tubes comprising tubes V20 and V21 are normally rendered plate current cut-off by the large negative bias potential (from source B2) applied upon their control grids through load resistors R47 and R48. The control grids of these tubes are driven by the major peak signals from input terminals (A) and (B), which represent the same output terminals of trigger tube V9 in Fig. 1. These selected major peak signals are coupled to the control grids of idle tubes V20

and V21 through coupling capacitors C44 and C45, respectively. As each tube (V20 or V21) becomes conductive by a positive major peak signal upon its control grid element, it draws current through the common plate circuit resistor R49, which in turn transmits a negative voltage signal to the control grid of normally operative tube V22 through coupling capacitor C46 and rectifier diode D8. The rectifier diode is used so that the signals impressed upon the control grid of V22 will be unidirectional. These unidirectional negative voltages are stored in the capacitor C47, which stores the repeatedly arriving negative voltage signals long enough to keep the normally conductive tube V22 from operating during a spoken sound received by the microphone 1, in Fig. 1. When the normally conducting tube V22 becomes inoperative, the normally energized relay RY1 (in the plate circuit of V22) becomes de-energized and the normally closed armature contact points 2 and 3 open, for producing a representative signal of word separation. Of course, these relay contact points could be arranged so that the contact points 2 and 3 would normally be open, and close when the relay is de-energized.

As mentioned in the foregoing, production of wave patterns in ordinary speech sounds has a frequency range of from 60 to 600 wave patterns per second. In pronouncing a series of words, however, the minimum time that the physical elements can go through in making a complete cycle of change in position is not less than $\frac{1}{10}$ of a second, or approximately thereof, before a succeeding word is pronounced. Since the negative voltage signals are stored in storage capacitor C47 at the frequency rate of said repeating wave patterns, the discharge time constant of capacitor C47 is adjusted by the parallel connected resistor R50 to be longer than the time period of a wave pattern having the longest time period, but not longer than $\frac{1}{10}$ of a second. By such pre-adjustment, the relay RY1 will remain de-energized during successive arrivals of major peak signals, and when this succession stops for about $\frac{1}{10}$ second the negative charge across capacitor C47 becomes dissipated by the parallel connected resistor R50, and consequently the tube V22 becomes conductive causing re-energization of relay RY1. Thus, during quiescence for at least $\frac{1}{10}$ second or longer, the relay RY1 sets itself in a position to represent a word count of the spoken words.

In the schematic arrangements of Figs. 1 and 6 it will be noted that numeral designations to various component parts are omitted for the sake of simplicity of drawing. The inclusion of these parts, however, will be obvious to the skilled in the art, as their uses are commonly known in the art of electronics. For example, the inclusion of load resistors at the first control grid elements of tubes V2—V7, and the control grid elements of triode tubes V14, V15 and V17 is of common use in this particular art. Also, the capacitor leading from the anode element of the right handed section of double triode V14 to ground is not designated. This particular capacitor had been added in the actual operating device for suppressing pick-up noise from external sources. However, it may be eliminated if lead capacitances of wiring of the constructed device are minimized. Numerical indications to the voltage dividing resistor and filtering bypass capacitors leading to the screen grid terminals of tubes V10—V13 are also omitted in the drawing, as they are self explanatory. Similarly, the same relates to the load resistors in Figs. 3 and 6, leading from the cathode elements of diodes D1 and D8, respectively, to ground; likewise, the cathode circuit resistors of triode tubes V14—V17 which are used for linear operation of said tubes; and of V20—V22 which are used for safety operation of said tubes, and they may be eliminated if so desired.

While in the foregoing I have described the principles of my invention in connection with specific apparatus, I wish it to be understood that this description and the

accompanying drawings thereof are made by way of limited examples only, as it will be obvious to the skilled in the art of electronics that various substitutions of parts, adaptations and modifications are possible without departing from the spirit and scope thereof.

What I claim is:

1. In speech sound waves where one cycle time reference points of variable fundamental frequencies are identified by major peaks of the waves, the system of exaggerating these peaks from minor peaks for selection of same, which comprises means for producing these speech sound waves; a first square-law gain-controllable amplifying means and means therefor for amplifying the produced sound waves; a first gain-suppressing unidirectional feedback coupling path between the amplified and produced sound waves and means therefor for feeding back the amplified waves for suppressing the gain of said amplifier in inverse proportion, and thereby compressing the higher amplified waves; a first gradually decaying storage means associated with said first gain-suppressing coupling path, whereby storing said unidirectional feedback waves in approximation of constant states, and thereby approximately equalizing the peak amplitude of said amplified sound waves; a second square-law gain-controllable amplifying means and means therefor for amplifying said amplitude equalized sound waves; a second gain-suppressing unidirectional feedback coupling path between the last said amplified and said amplitude equalized waves and means therefor for feeding back last said suppressing waves; a second gradually decaying storage means associated with the second coupling path for storing substantially the peak quantity of last said suppression waves, the decaying time constant of the second storage means being at least equal or longer than one cycle period of the average of said variable fundamental frequencies but short enough for the storage means to be capable of restoring a substantial quantity at successive arrivals of the major peaks, thereby causing suppression storage of the gain of said second amplifying means in larger magnified proportion at the beginning of each of said major peaks than at the minor peaks; and means for selecting the storage of larger proportions representative of said major peaks.
2. In complex waves where one cycle time reference points of variable fundamental frequencies are identified by major peaks of the waves, the system of exaggerating these major peaks from minor peaks for selection of same, which comprises means for producing complex waves; a first square-law gain-controllable amplifying means having first and second input and a first output terminals; means for applying the produced complex waves to said first input terminal for amplifying in said first output terminal; a first gain-suppressing unidirectional feedback coupling path between said output and second input terminals of the amplifier for suppression of said amplified waves in inverse proportion; a first gradually decaying storage means associated with said second input terminal, whereby storing said unidirectional feedback waves in approximation of constant states, and thereby approximately equalizing the peak amplitude of said amplified complex waves by way of said inverse-proportioned gain-suppression; a second square-law gain-controllable amplifying means having third and fourth input and second output terminals; means for applying said amplitude equalized waves to the third input terminal of said second gain-controllable amplifier for amplifying same at said second output terminal; a second gain-suppressing unidirectional feedback coupling path between said second output and fourth input terminals for suppressing the gain of said second amplifier; a second gradually decaying storage means associated with said fourth input terminal for storing substantially the peak quantity of last said suppression waves, the decaying time constant of the second storage means being at least equal or longer than one cycle period of the aver-

age of said variable fundamental frequencies but short enough for the storage means to be capable of restoring a substantial quantity at successive arrivals of the major peaks, whereby causing suppression storage of the gain of said second amplifying means in larger magnified proportion at the beginning of each of said major peaks than at the minor peaks; and means for selecting the storage of larger proportions representative of said major peaks.

3. In complex waves where one cycle time reference points of variable fundamental frequencies are identified by major peaks of the waves, the system of exaggerating these major peaks from minor peaks for selection of same, which comprises means for producing complex waves; a first square-law gain-controllable amplifying means having first and second input and a first output terminals; an impedance means in the first output terminal for amplifying the input waves in said impedance means; a first gain-suppression feedback coupling means comprising a rectifier means coupled unidirectionally from said impedance means to said second input terminal for suppressing the gain of said first amplifier in inverse proportion; a peak-limiting bias source associated with said rectifier means so as to allow passage of the amplified waves in said impedance means after reaching in magnitude greater than the peak-limiting bias source; a first gradually decaying storage means associated with said second input terminal, whereby storing said limited unidirectional feedback waves in approximation of constant states, and thereby approximately equalizing the peak amplitude of said amplified complex waves by way of said inverse-proportioned gain-suppression; a second square-law gain-controllable amplifying means having third and fourth input and second output terminals; means for applying said amplitude equalized waves to the third input terminal of said second gain-controllable amplifier for amplifying same at said second output terminal; a second gain-suppressing unidirectional feedback coupling path between said second output and fourth input terminals for suppressing the gain of said second amplifier; a second gradually decaying storage means associated with said fourth input terminal for storing substantially the peak quantity of last said suppression waves, the decaying time constant of the second storage means being at least equal or longer than one cycle period of the average of said variable fundamental frequencies but short enough for the storage means to be capable of restoring a substantial quantity at successive arrivals of the major peaks, whereby causing suppression storage of the gain of said second amplifying means in larger magnified proportion at the beginning of each of said major peaks than at the minor peaks; and means for selecting the storage of larger proportions as representations of said major peaks.

4. The system as set forth in claim 2, wherein said first square-law gain-controllable amplifying means, said first gain-suppressing feedback coupling path, and said first gradually decaying storage means comprise A and B square-law amplifying means, each having A and B input terminals and A output terminals; means for electrically coupling in parallel said B input terminals of the A and B amplifying means; means for applying said produced complex waves to said A input terminals of the A and B amplifying means in opposite polarities, for

amplifying said waves at the A output terminals in opposite polarities; an A gain-suppressing unidirectional feedback coupling path between said A output terminal of the B amplifying means and said parallel coupled input B terminals, for suppression of the amplified waves at said output A terminals in inverse proportion; an A gradually decaying storage means associated with said parallel coupled B terminals, whereby storing said unidirectional feedback waves in approximation of constant states, and thereby approximately equalizing the peak amplitudes of the amplified complex waves at the A output terminals of said A and B amplifying means by way of said inverse-proportioned gain-suppression; and means for applying the amplitude-controlled waves at the output A of said A amplifying means to the third input terminal of said second square-law gain-controllable amplifying means aforesaid.

5. The system as set forth in claim 3, wherein said first gain-controllable amplifying means, impedance means, first gain-suppressing feedback coupling means, and first gradually decaying storage means comprise A and B square-law amplifying means, each having A and B input terminals and A output terminals; means for electrically connecting in parallel said B input terminals of the A and B amplifying means; A and B impedance means in the A output terminals of the A and B amplifying means, respectively; means for applying said produced complex waves to said A input terminals of the A and B amplifying means in opposite polarities, for amplifying said waves across said A and B impedances, respectively, in opposite polarities; an A gain-suppressing unidirectional feedback coupling means comprising a rectifier means coupled unidirectionally from said B impedance means to said parallel connected B input terminals, for suppression of the amplified waves at said output A terminals in inverse proportion; an A gradually decaying storage means associated with said parallel connected B terminals, whereby storing said unidirectional feedback waves in approximation of constant states, and thereby approximately equalizing the peak amplitudes of the amplified complex waves at the A output terminals of said A and B amplifying means by way of said inverse-proportioned gain-suppression; and means for applying the amplitude-controlled waves across the A impedance means of said A amplifying means to the third input terminal of said second square-law gain-controllable amplifying means aforesaid.

6. The system as set forth in claim 1, wherein is included means for indicating the beginning or ending of a spoken word in speech, which comprises means for deriving successive signals from said selected storage of larger proportions representative of said major peaks; a third gradually decaying storage means having a decaying time constant equal approximately to the minimum time that the physical elements of the vocal system can go through in making a complete cycle of change; means for storing said derived successive signals in the third storage means; a switching means operatively responsive to last said storage; and means for deriving an output signal from each of the non-operating states of said switching means as a representation of the beginning or ending of a spoken word aforesaid.
